UNITED STATES PATENT OFFICE

MAXWELL S. HART, OF NEW BRITAIN, AND MAURICE G. STEELE, OF FARMINGTON, CONNECTICUT, ASSIGNORS TO THE HART & HUTCHINSON COMPANY, OF NEW BRITAIN, CONNECTICUT, A CORPORATION OF CONNECTICUT

AIR HEATING AND CIRCULATING APPARATUS

Application filed May 17, 1928. Serial No. 278,417.

This invention relates to air-circulating and heating systems for buildings, and more particularly to an improved form of fin-type extended surface radiator adapted to be located within the wall of a room.

One object of this invention is to provide a radiator stack having a lower grille opening for drawing cold air from the bottom of the room and an upper grille opening for delivering heated air to the top thereof.

A further object is to provide a housing at the bottom of the stack for covering the front of the radiator, said housing having a lower grille opening located at an elevated position above the floor of the room for permitting a broad stream of air to be drawn into the radiator stack.

A further object is to provide a housing at the lower part of the stack containing the lower grille opening, said grille being so positioned as to prevent air from entering the stack except through the fins of the radiator.

A further object is to provide an apparatus of the above nature which will be simple in construction, inexpensive to manufacture, easy to install and manipulate, compact, ornamental in appearance, and very efficient and durable in use.

With these and other objects in view there has been illustrated on the accompanying drawings one form in which the invention may be conveniently embodied in practice.

Fig. 1 represents a front view of the radiator as it appears when installed within a wall of a room.

Fig. 2 is a side sectional view of the same.

Fig. 3 is a top view of the radiator unit.

Fig. 4 is a front view of the same, the bottom header being shown partly in section.

Fig. 5 is an end view of the radiator unit.

Fig. 6 is a fragmentary sectional view showing one of the compression couplings for connecting the ends of the radiator tubes with a header.

Referring now to the drawings in which like reference numerals denote corresponding parts throughout the several views, the radiator unit comprises a pair of upper and lower rectangular headers 10 and 11 of square cross-section connected together by two rows

of staggered tubes 12 and 13 respectively. The tubes 12 and 13 are surrounded by a plurality of vertically-spaced horizontally-extending inclined fins 13a, preferably soldered to said tubes 12 and 13.

In order to form a leak-proof detachable connection between the tubes and the headers, the ends 14 of the tubes are adapted to fit within annular seats 15 formed near the lower ends of socket openings 16 leading to the interior 17 of the headers, one such connection being clearly shown in Fig. 6. Each of the tube ends 14 is adapted to be securely locked in its seat 15 by a compression coupling member 18 which is exteriorly threaded and has a hexagonal wrench-engaging section 19 on one end and a tapered annular rim 20 on its other end. The coupling members 18 are adapted to be screwed into correspondingly threaded sections 21 of larger diameter than the tube seats 15, said threaded sections being joined to said seats by inclined convex shoulders 21a.

By means of this construction, when the coupling members 18 are screwed into the header socket openings 16, the annular rims 20 of said coupling members will engage the inclined shoulders 21a and will be forced inwardly against the exterior surface of the tubes, thereby forming a tight leak-proof connection therewith. It will be understood, however, that the tubes may be easily detached from the headers merely by rotating the coupling members 18 at the opposite ends of said tubes in the reverse direction from that just described. The headers 10 and 11 may then be separated relative to each other, whereupon the entire bank of tubes and fins may be removed for cleaning or other purposes.

In order to permit the headers to be readily cleaned, provision is made of detachable countersunk closure plugs 23 in the opposite ends thereof.

The steam, hot water, or other heating medium is permitted to enter the radiator through an inlet pipe 25 located behind the tubes 12 and 13, said pipe 25 being connected by an elbow 26 to the upper header 10, whereby the heating medium will be

caused to pass downwardly through the tubes 12 and 13 and will leave the radiator unit at the bottom through an outlet pipe 27 connected to the lower header 11.

5 Provision is also made of a standard form of radiator air valve 28 connected to the top of the lower header 11 for allowing air to escape but preventing loss of the heating medium from the radiator.

10 The radiator unit just described is adapted to be located within a radiator stack 29 positioned within the wall of a room, said stack extending upwardly from the floor 30 of said room and terminating in a top wall 31. The radiator stack 29 is preferably arranged within the framing, studding, or chase in one of the walls of a room so that the front of the stack may be subsequently covered with lath or plaster to conceal said stack.

15 20 A pivoted damper 32 is suspended from said top wall 31 and has an operating handle 33 whereby it may be swung about its pivot to regulate the flow of heated air to the room through an upper front opening 34 of the stack 29 and an upper ornamental grille member 35.

25 In order to support the radiator unit in position within the lower part of the stack 30 29, provision is made of a pair of bracket members 36 riveted or otherwise secured to the sides of said stack. The lower front part of the stack 29 is left open at 37 for permitting the radiator unit to extend out 35 somewhat into the room, and said radiator unit is adapted to be concealed by a housing 38 resting on the floor 30 and having its upper end curved inwardly at 39 to fit snugly against the portion 40 of the wall in front of the stack 29. Intermediate its upper and 40 lower ends the housing 38 has a forwardly extending rectangular lower grille section 41 which has an opening adjacent to and coinciding with the front vertical heating area 45 of the bank of radiator fins, whereby all of the air drawn from the bottom of the room will be passed through the heating fins before it rises in the stack 29. The inlet and outlet pipes 25 and 27 are connected to the 50 main heating system by a pair of unions 42 and 43, and it will be understood that by unscrewing said unions, the entire radiator unit may be easily withdrawn from the stack whenever desired.

55 In operation, the flow of air in the room will be in a relatively smooth curved path without abrupt turns. Dead air spaces will thus be avoided, and due to the chimney draft 60 effect of the high stack and the fact that the inclined fins are in alinement with the natural course of the air circulation, the resistance to the flow will be minimized and the circulation of air in the room and the 65 radiator system will be quite rapid, thereby

producing uniformity of temperature throughout the room.

One advantage of the present invention is that the heating unit occupies but little space within the room and owing to the attractive arrangement of the grilles adds considerably to the ornamental appearance thereof.

A further advantage of the present vertical construction of the radiator unit is that it utilizes only a small width of wall space in 75 proportion to its heating capacity.

A still further advantage of the present invention is that the lower radiator housing is easily removable making the radiator unit quite accessible for cleaning or repairs.

80 While there has been disclosed in this specification one form in which the invention may be embodied, it is to be understood that this form is shown for the purpose of illustration only, and that the invention is 85 not to be limited to the specific disclosure but may be modified and embodied in various other forms without departing from its spirit. In short, the invention includes all the modifications and embodiments coming 90 within the scope of the following claim.

Having thus fully described the invention, what is claimed as new, and for which it is desired to secure Letters Patent, is:

95 In an apparatus for heating and circulating the air in a room, a wall stack having upper and lower openings leading into said room, a grille covering said lower opening and having an offset portion projecting forwardly into the room, a radiator located in 100 said lower opening and having fins extending into the offset portion of said grille, whereby the air entering the stack through said lower opening will be efficiently heated as it passes over said radiator and its fins.

105 In testimony whereof, we have affixed our signatures to this specification.

MAXWELL S. HART.
MAURICE G. STEELE.
